UNITED STATES PATENT OFFICE.

HAROLD A. SOULIS, OF NEW YORK, N. Y., ASSIGNOR TO UNITED SHOE MACHINERY COMPANY, OF PATERSON, NEW JERSEY, A CORPORATION OF NEW JERSEY.

HEEL-BREASTING MACHINE.

1,109,709.

Specification of Letters Patent.

Patented Sept. 8, 1914.

Application filed August 16, 1912. Serial No. 715,440.

To all whom it may concern:

Be it known that I, HAROLD A. SOULIS, a citizen of the United States, residing at New York, in the county of New York and State 5 of New York, have invented certain Improvements in Heel-Breasting Machines, of which the following description, in connection with the accompanying drawings, is a specification, like reference characters on 10 the drawings indicating like parts in the several figures.

This invention relates to heel-breasting machines and particularly to the gage or presser plate usually employed in such machines to engage the tread face of the heel and serve to position the work and hold it during the heel-breasting operation.

In certain types of shoes, the top lift or tread portion of the heel is provided with 20 projections, such for example as metallic calks or studs commonly used in sporting shoes to prevent slipping, and it has been difficult, if not impossible, to breast such shoes on a machine after the heels have been 25 attached.

It is the object of this invention to modify and adapt a machine to breast shoes the heels of which have the characteristics mentioned or similar ones.

To this end a feature of this invention 30 consists in the novel construction of a presser plate for clamping engagement with the tread face of a heel which has projections standing above its surface.

A more particular feature of the invention 35 comprises a tread plate having a thickness somewhat greater than the length of the longest stud or calk to be used, and in the plate holes or recesses extending from its lower side upwardly are formed which 40 are adapted to receive the studs or calks of the heel so that the surface of the tread plate surrounding said recesses may come in direct contact with the tread face of the 45 heel and the heel may therefore be clamped firmly in position during the operation of 50 breeding. The calks are usually arranged in parallel lines extending longitudinally of the heel and accordingly it is preferable to form the recesses of the presser plate as 55 grooves or slots extending lengthwise thereof so that the shoe may be drawn lengthwise from under the plate without lowering it sufficiently to bring the projecting ends

of the calks below the lower face of the 55 plate, as is necessary when the recesses are in the form of holes.

These and other features of the invention will appear more fully from the following detailed description, when taken in connection 60 with the accompanying drawing and the appended claims.

Figure 1 is a side elevation, partly in section, of the portion of the breeding machine which supports the tread plate and 65 shows the relation of the knife and the shoe to the tread plate; Fig. 2 is a plan view of the plate, the relation of the shoe to the plate being shown in full and dotted lines.

Referring to Fig. 1 of the drawing, 2 indicates the lower portion of the slide of a breeding machine of the type referred to above which carries the holder for the tread or presser plate. The holder comprises a block 4 which is pivoted at 6 to the slide 2 70 and is normally maintained with its upstanding portion 8 against an adjusting screw 10 by a spring 12 which is attached between pins 11 and 13 which are arranged in a line above the center 6. The tread plate 80 14 is held in the lower face of the block 4 by a headed stud 16 and a wing nut 18, which is threaded onto a stud 20 extending downwardly from the block 4. A slot 22, Fig. 2, permits adjustment of the plate relatively to the stud 20. The presser plate 14 is provided on the under side of its forward portion with grooves extending longitudinally of the plate and of the shoe, the slots 24 being open at the forward end. Between 85 the grooves 24 are ribs 26, the lower faces of which lie in the plane of the lower face of the plate 14 and are adapted to engage the tread face of the top lift between the studs extending upwardly from the face 90 of the heel, as indicated at *a*, Fig. 1. The slots 24 are preferably made wide enough to embrace not only the upper portion of the stud but also the collar on the stud which 95 engages the surface of the top lift. The forward edge of the plate 14 and the forward ends of the ribs 26 are beveled off and the ends of the ribs together with the un-grooved portion of the plate may serve as 100 the guide for positioning the heel so that the breeding cut will be made at the proper point in the heel, it being understood that 105 the plate 14 is so adjusted longitudinally

that the forward ends of the ribs 26 lie just to the rear of the line where the knife 30 cuts the heel.

If desired, openings may be made completely through the plate as at 32 to accommodate longer calks than those shown, the shoe being removed from operative position by first moving the plate 14 and the shoe relatively vertically and then moving the shoe outwardly, the sides passing along the grooves 24. It is also within my invention to provide the plate 14 with holes properly located to receive the studs of the heel without the grooves 24, in which case the shoe and plate 14 must be moved relatively vertically to a sufficient extent to free the studs from the holes in the plate, so that the shoe may be swung outwardly from beneath the plate 14.

Having described my invention, what I claim as new and desire to secure by Letters Patent of the United States is:—

1. A heel breasting machine, having, in combination, a tread plate holder, and a tread plate secured thereto having recesses formed to receive projections on the tread face of the heel, said plate being of a thickness to space the tread face of the heel away from the holder a distance greater than the height of the projections.

2. A tread plate for heel breasting machines adapted for use in breasting a heel

having projections inserted therein, comprising a plate with recesses extending along the tread face longitudinally of the heel and opening through the breast end of the plate, said recesses being of greater depth than the height of the projections.

3. In a machine of the class described for breasting heels having projections thereon, the combination of a holder and a member for applying pressure to the tread surface of the heel being breasted comprising bearings adapted to extend longitudinally of the heel between the said projections and to apply pressure to the surface of the heel when the holder is forced toward the heel and to permit retraction of the heel longitudinally from beneath the member when the pressure is released.

4. A tread plate for machines for breasting heels having projections extending from their tread faces, comprising a plate with recesses extending along the tread face of the plate longitudinally of the heel and opening through the breast end of the plate.

In testimony whereof I have signed my name to this specification in the presence of subscribing witnesses.

HAROLD A. SOULIS.
